Application October 29, 1936, Serial No. 65,569

Term of patent 14 years

To all whom it may concern:

Be it known that I, Alexis de Sakhnoffsky, a subject of the former Czarist Regime of Russia, residing at Philadelphia, in the county of Philadelphia and State of Pennsylvania, have invented a new, original, and ornamental Design for a Vehicle, of which the following is a specification, reference being had to the accompanying drawing which forms a part thereof.

Fig. 1 is a side elevation of a vehicle embodying the design.

Fig. 2 is a plan view of the vehicle shown in Fig. 1.

Fig. 3 is a perspective view of the lowermost rear portion of the tractor shown in Fig. 1.

While I have shown in Figure 1 a side elevation of the right-hand side of the vehicle, it will be understood that the left-hand side elevation would appear the same.

I claim:

The ornamental design for a vehicle substantially as shown and described.
